UNITED STATES PATENT OFFICE.

WILLIAM F. MARRESFORD, OF BROOKLYN, NEW YORK.

MACHINE FOR MAKING CUT-OUT WALL-PAPER.

1,223,892.

Specification of Letters Patent.

Patented Apr. 24, 1917.

Application filed August 10, 1912. Serial No. 714,432.

To all whom it may concern:

Be it known that I, WILLIAM F. MARRESFORD, a citizen of the United States, residing at Brooklyn, in the county of Kings and 5 State of New York, have invented certain new and useful Improvements in Machines for Making Cut-Out Wall-Paper, of which the following is a full, clear, and exact specification.

10 This invention relates to a machine for making cutout wall paper, such as borders, friezes, crowns, binders, rosettes, corners, etc., which are applied to walls in conjunction with the body finish for the purpose of increased decoration. These "cutouts" are 15 largely used at the present time for decorating purposes, and, as heretofore made and sold to the trade, have been printed, dried, cut and then wound in rolls with a filling 20 paper, ready for use. When used by the paper hanger the filling paper is thrown away.

The object of the present invention is to 25 combine a web cutting apparatus with a web printing machine in such manner that a design of line perforations or cuts will be formed on the web immediately before it enters the printing machine and in exact 30 synchronism with the design to be printed, so that the printed cutout can be wound in rolls or subsequently treated like ordinary 35 printed wall paper without any filling paper and separated by the paper hanger at the work by tearing the uncut portions, leaving the cutout design with clean and sharp edges 40 requiring no further trimming or cutting before being put up.

This invention is distinguished from prior 45 machines for other purposes which sever the web with a continuous cut, in that a succession of intermittent cuts are made along the edge of the portion to be decorated, so that in subsequent treatment, such as printing and drying, the unitary character of the web 50 can be retained. The use of numerous elongated knives for cutting the decorative design in a web before printing, as compared with perforating pins which simply displace and upset the surface of the material after printing is an important feature of 55 this invention. A needle raises a bur on

the paper, which tends to cause trouble in the printing machine because of the uneven surface, and also necessitates a very great number of holes, whereas I have found that 55 a paper web can be cut without objectionable burs by a succession of edged knives in any desired design and then subsequently printed or otherwise treated during the same operation, before the waste part is completely separated, without warping or displacing the cuts and the design.

The invention, with reference to its details and advantages, will be more fully understood in connection with the accompanying drawings, wherein—

Figure 1 is an elevation of a portion of a multicolor printing machine having the cutting apparatus of this invention combined therewith; and

Figs. 2 to 6, inclusive, show details of the cutting mechanism.

1 represents a portion of the frame of a multicolor web printing machine having the printing roller 2, and color rolls 3, 3, all of 75 which are constructed in a well understood manner so that each roll 3 prints a different color and all are driven in synchronism with the roll 2 by means of a large gear 4 meshing with driving gears on the shafts of rolls 80 3, and with driving gear 5. 6, 6, 6 are idler rolls over which the web 7 runs and 8, 8 are tension rolls or bars. 9 represents an auxiliary frame for the cutting mechanism which is herein shown as attached to 85 an extension of the main frame 1, but which may be otherwise supported, if desired. 10 is a counter or platen roller provided with a resilient surface 11 between which and the cutting roller 12 the web 7 runs, and is at 90 the same time fed thereby. In order to properly effect the cutting of the web, it will be seen that the web is bent around the platen, so that it is under tension and at the same time flattened and firmly held on the 95 yielding platen surface while in contact with the knife pins.

The counter or platen roll 10 and the cutting roll 12 are provided with intermeshing gears 13, 14, the latter meshing with gear 15 100 which gears with gear 5 above described, so that the cutting roller 12 and the counter

roller 10 will be positively driven in exact synchronism with the printing rolls 3, and each other, so that the web is simultaneously fed and cut exactly in synchronism with the printing design rolls 3.

The platen or counter roller 10 is provided with a shaft 16 which is carried by levers 17 journaled at one end 18 in the auxiliary frame 9 and having at the opposite end 19 a link 20 pivoted at 21 to a lever 22 journaled at 23 on the frame 9. By pressing down on lever 22 the counter roller 10 will be lifted from engagement with the cutting roller 12. To control the contact between the resilient surface 11 of counter roller 10 and the cutting roller 12, a set screw stop 24 is provided which can be adjusted up or down to support the short end of lever 22. When it is desired to remove the cutting mechanism, a hook 25 on chain 26 is engaged with a transverse bar 27 connecting the lower ends of side frames 9, thereby lifting the counter platen clear of the cutting means. The platen roller 10 is preferably made wider than the web, so that it can be shifted on the shaft to change the cutting surface, and it is also driven by an uneven gear, so that it will not coincide with the design, thereby prolonging the life of the resilient covering.

The movable frame 28 consists of two side frames connected by a tie rod 34 and each pivoted at 29 on the shaft of the gear 5, thus permitting the cutting roller 12 to be swung toward and from the platen roller 10 without changing the meshing of gears 5, 14, 15. The bearings of roller 12 are thus adjustable toward and from the platen, to allow for various sizes of platen rollers. The intermediate idler gear 15 is carried on a shaft 30 which is adjustable in a slot 31 of the swinging side frame 28, so that when cutting roll 12 is changed in diameter, gear 14 will be likewise changed to correspond, and still be driven synchronously with the printing rollers 3.

Inasmuch as color printing machines are arranged so that various diameters of printing rolls are to be used according to the patterns to be printed, it is desirable in the operation of this machine that the cutting roll be of the same circumference as the printing rolls, which is provided for by first adjusting the frames 28 relatively to frame 9 by pins 32 passed through holes 33, the holes 33 being spaced in accordance with standard circumferences of cutting rolls, which latter will be made in circumferences corresponding to the standard diameters of printing rolls 3, or multiples thereof if a pattern is repeated. The cutting roller 12 is preferably mounted in open bearings so that upon lifting the counter roller 10, it can be lifted in and out, it being

seen that the side frames 9 and 28 are curved ⁶⁵ to facilitate this operation.

The particular construction of cutting means is not described and claimed in this application but in a divisional application filed August 11, 1913, Serial No. 784,078. ⁷⁰

As preferred by me, the periphery of roll 12 is made of wood, and V-edged spaced knife pins are driven therein in accordance with the design or designs to be cut. It will be seen that several designs on a single ⁷⁵ web may be cut and printed at one operation where desired.

Fig. 2 shows the details of the knife roll 12. It comprises a body or center of suitable material with a periphery ⁸⁰ 35 of wood or other material into which the knife pins can be driven. These knife pins are similar to wire nails, except that instead of having driving heads they are provided with knife edged heads 37, preferably pointed ⁸⁵ as shown, but cutting an elongated slit by severing the fibers, as distinguished both from a needle point which merely perforates and displaces the fibers, and a punch which cuts holes and removes the material. ⁹⁰ Below the flattened blade portion driving shoulders are formed on the shanks 36 so that the cutting edges 38 will not be damaged in driving. The flattened blade portion ⁹⁵ 37 is of less thickness than the shank portion 36, and the designs 39 and 40 are formed on the surface of roller 12 in Fig. 2 by driving into the surface the requisite number of knives to form the outline to be cut in the paper. These knife edges will ¹⁰⁰ all be set to lie on the same circumference. In order to make sharp curves, indentations, etc., in the line of cuts or slits, to form angles, etc., the shanks 36 are preferably made round in cross section so that they can ¹⁰⁵ be turned or angularly adjusted after having been driven in the roller, and the sides of the flat portions preferably taper toward the base so that the knife pins can be set on radii of the roller 12. This also enables ¹¹⁰ the knife pins to be initially set with a slight space between them as shown in Fig. 4, and subsequently to be driven farther in without displacement, as may be necessary when the printing rollers are re-surfaced, ¹¹⁵ and therefore made of smaller diameter.

It is to be observed that the cut designs on the web will bear a predetermined relation to the printed designs, which will work out in practice, because there is no opportunity for stretching of the web between the time it is cut and the time it is printed, it being well known that even slight dampening of a web causes it to stretch and warp and renders it necessary that the cutting and printing devices be very closely disposed relatively to each other and that they operate as nearly simultaneously as possible. ¹²⁰ ¹²⁵

It is, therefore, more advantageous to cut the web before it is printed than after, because after the web is printed, especially where a number of colors are printed, it 5 becomes damp and liable to stretch, and the amount of stretch varies with the particular web in many instances so that exact registering is more easily obtained by the specific arrangements of the parts herein 10 shown. When dampened by paste, the design is readily separated along the line of cuts by tearing, and the paper cuts more smoothly when dry. Moreover, it will be observed that the cutting devices act on 15 the face of the web, so that any roughened edges will appear on the back, thereby not affecting the lay of the color.

From the foregoing description it will be seen that by the present invention, it is for 20 the first time practicable, so far as I am aware, in the wall paper art to commercially produce at one operation cutouts in widely varying patterns which will register exactly with the printed patterns and which 25 can be sold to the trade in rolls like ordinary wall paper, whereby the cost of filling paper is saved and also the loss of time and expense involved in the present methods of producing cutouts in the factory both 30 in the production of cutting dies and in the actual work of cutting the paper.

By this invention much more ornamental and elaborate shelf papers can be produced than those now on the market, which can be 35 cut, printed and wound in rolls like wall paper instead of being cut by dies and sold flat, as is now common practice.

Various modifications and changes in the specific devices herein described for producing the cutout, and in the cutout itself, may 40 be made without departing from the scope of the invention.

Having thus described my invention, I declare that what I claim as new and desire to 45 secure by Letters Patent is:

1. In a machine for decorating a web of paper or similar material, the combination with a rotary cylinder printing machine having at least one design printing cylinder, 50 of a web cutting means arranged to approximately simultaneously cut a design in predetermined relation to the design printing cylinder, a platen also driven synchronously with said cutting means and said printing cylinder to feed the web to said printing machine, said cutting means being mounted to be moved toward and from said platen and said platen being mounted to move toward 55 and from said cutting means.

2. The combination with a decorative design web printing roller, of a cutting roller driven in synchronism with said printing roller and having on its periphery a succession of separate cutting knife edges to form

a separable line of slits in the web corresponding to the design approximately simultaneously printed by said printing roller. 65

3. The combination with a decorative design web printing roller, of a cutting roller driven in synchronism with said printing roller and having on its periphery a succession of separate individually adjustable knife edges to form a separable line of slits in the web corresponding to the design approximately simultaneously printed by said 70 printing roller. 75

4. In wall paper manufacture, and in combination with means for continuously applying a design to a web, means immediately adjacent and synchronized with said 80 design applying means for approximately simultaneously and continuously effecting in the web a close linear succession of slits outlining said design in fixed relation thereto, whereby said web is capable of further handling as an entirety and the design bearing portion rendered separable by tearing the portions between successive slits. 85

5. The combination with a decorative design printing roller, of a cutting roller 90 driven in synchronism with said printing roller and having on its periphery a succession of separate cutting knife edges to approximately simultaneously form a line of cuts in the web corresponding to the design 95 printed by said printing roller, and a platen driven synchronously with said cutting roller to support and feed the web as said knife edges successively cut the design.

6. The combination with a decorative design printing roller, of a cutting roller driven in synchronism with said printing roller and having on its periphery a succession of separate cutting knife edges to approximately simultaneously form a line 100 of cuts in the web corresponding to the design printed by said printing roller, and a platen driven synchronously with said cutting roller to support and feed the web as said knife edges successively cut the design, 105 110 said platen and cutting roller being relatively adjustable to regulate the pressure at the cutting point.

7. The combination with a decorative design web printing roller, of a cutting roller 115 driven in synchronism with said printing roller and having on its periphery a succession of separate cutting knife edges to approximately simultaneously form a line of cuts in the web corresponding to the design 120 printed by said printing roller, said knife edges being disposed on the face side of the web, and a cutting platen coöoperating with said knife edges on the rear side of the web.

8. The combination with a decorative design printing roller, of a cutting roller driven in synchronism with said printing roller and having on its periphery a succes-

sion of separate cutting knife edges to approximately simultaneously form a line of cuts in the web corresponding to and in advance of the design printed by said printing 5 roller, and a platen driven synchronously with said cutting roller to support and feed the web as said knife edges successively cut the design, said platen and cutting roller

being independently adjustable toward and from each other.

In testimony whereof I affix my signature, in presence of two witnesses.

WILLIAM F. MARRESFORD.
